(57) **CLAIM**

The ornamental design for a robot, as shown and described.

DESCRIPTION

FIG. 1 is a front view of a robot, showing our new design;
FIG. 2 is a rear view thereof;
FIG. 3 is a top plan view thereof;
FIG. 4 is a bottom view thereof;
FIG. 5 is a side elevation of the robot as seen from the right side of FIG. 1; the opposite side elevation is a mirror image thereto; and,
FIG. 6 is a rear perspective view thereof.
